FRANK F. WOLF, OF CATTARAUGUS, NEW YORK, ASSIGNOR TO OAKES & BURGER CO., INC., OF CATTARAUGUS, NEW YORK, A CORPORATION OF NEW YORK

CAN DELIVERY MECHANISM

Application filed November 4, 1930. Serial No. 493,300.

This invention relates to improvements in can washing machines and more particularly to a delivery mechanism therefor which is operative to receive the cans and their respective covers after the cleaning operation, to up-end the cans to an upright position, to place the covers upon them and to move the covered cans to a position where they may be readily removed by an attendant or otherwise.

One object of the invention is a novel construction and arrangement of the various parts utilized in the performance of the several operations whereby simplicity of construction and operation is obtained.

A further object is to provide a mechanism in which the moving parts are positively operated in timed relation with the cleaning equipment whereby the said mechanism is conditioned to effect delivery of the covered cans at the rate they are cleaned.

The invention is illustrated in the accompanying drawings, in which:—

Figure 1 is a side elevation of the delivery mechanism showing the position of the parts as they appear at the instant a cover is being applied to a can.

Figure 2 is a similar elevation of the opposite side of the mechanism.

Figure 3 is a section taken along line 3—3 of Fig. 1.

Figure 4 is a front elevation of the delivery end of the mechanism.

Figure 5 is a detail section of the operating mechanism of the can reversing means and is taken along line 5—5 of Fig. 1.

Figure 6 is a detailed view showing in plan the can reversing means, the parts thereof being shown as they appear while the can is moving by gravity from a substantially horizontal position to an up-ended position.

Figure 7 is an enlarged view in plan of the cover applying means.

Figure 8 is a transverse section of the same taken along line 8—8 of Fig. 7.

Figure 9 is a detail section of the can re-

versing means taken along line 9—9 of Fig. 3.

Figure 10 is a detail section of the operating mechanism for the can reversing means taken along line 10—10 of Fig. 1.

The delivery mechanism, as illustrated, is designed especially for use in connection with a machine for washing milk cans and the covers therefor. As in general practice, the cans while inverted are advanced through the cleaning machine simultaneously with their covers, the latter being discharged from an elevated guideway. While the cans and covers may be advanced through the cleaning machine and treated therein in the manner desired, this is preferably accomplished by the machine which forms the subject matter of my copending application, Serial No. 439,299, the discharge end of such a machine being indicated generally at C. As illustrated, therefore, the cans 15 are moved through the cleaning machine toward the delivery mechanism along rail supports 23 by fingers 17 between guide rails 16, the said fingers being adapted to advance the cans along the rail supports 23 step-by-step. The can covers 18 are, as shown, moved through the cleaning machine toward the delivery mechanism along an elevated guideway 19 by a chain 20, the latter being provided with fingers 21 which engage the covers to push them along the said guideway.

The delivery mechanism is adapted upon receiving a can and its cover, to up-end the former, after which operation it is moved while up-ended toward the cover receiving position. The cover which is delivered to the delivery mechanism has, in the meantime moved in advance of the can and is supported in the delivery mechanism above the mouth of the can. As the latter is advanced the cover is lowered, the cover applying mechanism and the can advancing means co-operating so that as the can reaches the cover applying position, the cover is lowered into the mouth of the can. As the can continues

to move forward under the influence of the can advancing means, the can carries its cover out of the cover applying mechanism.

The mechanism by which the cans are upended as they are discharged from the cleaning machine includes a downwardly inclined support 22 which arranges to provide an extension of the rail supports 23. Co-operating with the support 22 is an inverted V-shaped member 24, one leg 25 of which abuts the support 22 adjacent its bottom end, the said member being adapted to provide a shoulder. When a can moves off the rail supports 23, it tips forward by gravity and the lip thereof drops into the corner provided by the leg 25 of the member 24 and the support 22. As the can continues to fall, its breast drops upon the shoulder providing member 24, whereupon the lip of the can leaves the position it occupies and moves upwardly as the body of the can approaches a horizontal position.

Means is provided for arresting the upending movement of the can as it approaches a substantially horizontal position. The said means resembles, to some extent, a trough open at both ends, the downwardly converging sides of which are spaced so that their bottom edges delimit a rectangular opening 30 when in the can receiving position. One side 26 of the trough, as illustrated, is inclined slightly upwardly in the direction of its front end and is preferably fixed against movement as by strap and angle members 27 and 28 respectively. The other side 29 of the trough is designed for pivotal movement whereby its outer or free end may be moved toward and away from the outer end of the fixed side member 26. To this end, it is secured as by welding to an angle member 30 (see Fig. 4). The latter carries a vertical stub shaft 31 which is mounted in a bearing 32, the said bearing being suitably secured to a frame member 33, as best shown in Figs. 5 and 9. A link 34 is fixed to the end of the stub shaft 31 and at its opposite end the link is connected by a second link 35 to a slide block 36. As illustrated in detail in Figure 10, this block is formed from spaced bars 37 to which are secured plates 38 which overlie channel members 39, the latter being supported by means of depending straps 40 from the frame of the machine, it being understood that the said channel members provide a guideway in which the slide block 36 may move back and forth.

The slide block 36 is connected by a link 41 to the upper end of a lever 42. The latter is supported intermediate its ends upon a pin 43 which is mounted in a suitable bearing block carried by a frame member of the machine. At its lower end, the lever 42 is connected by means of a rod 45 to a lever 46, the latter being pivotally mounted at its lower end in a bearing block 47. The lever

46 carries a roller 48 which rides in a cam groove 49 provided by a cam wheel 50. The cam wheel is mounted upon a transversely extending shaft 51 which is connected through suitable reduction gearing to a drive shaft 52, the said gearing being indicated by a showing of its casing 53 (see Fig. 2). It will thus be apparent that as the cam wheel 50 is rotated the roller 48 travelling in the cam groove 49 causes the lever 46 to oscillate between determined limits. This movement is transmitted by the link 45 to the lever 42 which causes the slide block 36 to reciprocate in its guideway. As the slide block 36 moves back and forth in this manner, it causes the free end of the side member 29 of the trough to move toward and away from the outer fixed end of the companion side member 26.

The cam track 49 is so formed that the pivoted side member 29 of the trough is moved to the position shown in Figure 3, e. g. substantially parallel to the companion fixed side member 26, at the instant that a can is moved off the ends of the rail supports 23. The pivoted side member 29 remains in this position for a period of time sufficient to permit the can to tip forwardly and be received between it and the companion side member 26 in a substantially horizontal position. As the can is supported in this position, the cam wheel 50 continues to revolve thereby causing the free end of the side member 29 of the trough to move away from the adjacent end of the fixed side member. The normal opening formed beneath the can by the side members of the trough is thus increased by degrees from an opening delimited by substantially parallel sides to one in which the sides diverge in the direction of the bottom of the can to a predetermined extent. It will be apparent that as the free end of the pivoted side member 29 of the trough moves away from the adjacent end of the companion side member, the bottom of the can moves downwardly a short distance as it follows the sides of the trough. However, as the free end of the pivoted side member continues to move away from the fixed side member, a point is reached where the can is supported beyond its center of gravity in the direction of its top. When this point is reached, the can tips toward an upright position and slides downwardly between the side members of the trough. It is to be understood that while the can may be up-ended by the use of a single pivoted side member as described, both side members may be pivoted if desired and in either case they function in substantially the same manner.

As the can passes between the side members 26 and 29 of the trough, it is shifted bodily be a deflector plate 54 laterally of its previous path of travel upon a second pair of rail supports 55, along which it is moved on its bottom toward the cover receiving position. The

can is moved by a chain 56 which carries fingers 57 which engage the back of the can to push it along. The chain 56 may be driven by a suitable sprocket from the transverse shaft 51. From the reversing trough, the can is guided along the rails 55 on one side by a guide plate 59 and on the other side by a guide bar 59a.

The cover of the can has, in the meantime, moved out of the guideway 19 of the cleaning machine into the delivery mechanism and is supported thereby in advance of the can over the position at which it is to be applied to the latter so that as the can reaches the cover receiving position the cover may be applied thereto. The means by which this is accomplished includes a cover applying guide section 60 which is mounted at its inner end for pivotal movement upon pins 61 suitably mounted in the frame of the machine. The guide section 60 is arranged to receive at its pivoted end the can cover as it is discharged from the cleaning machine at about the same time that the can therefor is being discharged. The cover applying guide section, as best shown in Figures 7 and 8 is composed of a track or bar 62 upon which the cover may roll along its side toward the discharge end of the guide section and guide rods 63, 64, 65 and 66, the said bar 62 and rods being supported by side frames 62a to delimit a passageway for the cover. At its outer end the guide rod 63 is bent inwardly as at 63a as is also the outer end of the bar 62. However, the angle at which the bent portion 63a is bent inwardly is greater than the angle at which the bent portion of the bar 62 is bent and hence the two bent portions converge toward their outer ends. As the rod 63 is a substantial distance above the bar 62, the bent portion 63a acting against the flange of the cover tips the latter in the direction of the top guide rod 65, it being noted that this rod, as well as the lower rod 66, is bent inwardly so as to increase the width of the passageway at this point to accommodate the cover as it is tipped to an upright position. The cover in its upright position is supported by its flange upon the parallel terminal portions 68 of a rod 67, the said terminal portions preferably being inclined upwardly at a slight angle away from the pivoted end of the section 60. In the embodiment illustrated, one of the said terminal portions is connected to the bar 62 while the other terminal portion is connected to the ends of the guide rods 65 and 66. Beyond the supporting terminal portions 68, the rod 67 is bent to form an opening 70 through which the flange or head of the cover may pass as it moves off the said supporting terminal portions. It will thus be apparent that the cover which is discharged from the cleaning machine from the cover guide 19 may roll down the passageway provided by the bar

and guide rods and be righted above the position in which it is to be applied upon the supporting terminal portions 68 of the rod 67 during such movement. In order to arrest the cover upon the supporting terminal portions, the discharge opening 70 is normally closed by a gate 71 which is supported from a horizontal portion 72 of the rod 67.

In accordance with the invention, the cover is supported in advance of the can above its mouth and as the can reaches the cover receiving position the cover is lowered into the mouth of the can. The pivoted cover applying guide section 60, is therefore, connected by a rod 73 to a crank 74 which is carried by a transversely extending shaft 75. A second crank 76 is fixed to this shaft adjacent its opposite end and the said crank is connected by a rod 77 to the lower end of the lever 42. The rod 73 as best shown in Figure 2, is connected to the outer end of the pivoted cover applying guide section by a fork-shaped extension 78. This extension provides a lost motion connection between the rod 73 and a pin 79 which extends from the cover guide section. At the limit of its upward movement the cover applying section is preferably inclined slightly downwardly in the direction of the cover applying position. The rod 73 is actuated to lower the outer end of the cover applying guide section and hence the cover carried thereby toward the plane in which the mouth of the can is moving so that as the can reaches the cover receiving position its cover is lowered into the mouth of the can in the manner shown in Fig. 2. In this position, the terminal portions 68 of the rod 67 which normally support the cover rest upon the lip of the can. It is to be noted that the rod 73 is lowered to such an extent that the pin 79 is intermediate the ends of the slot formed by the extension 78 and that the free end of the pivoted cover applying guide section rests upon the can. As the can is advanced further, the free end of the said section continues to lower while the cover moves out of the opening 70 against the action of the swinging gate 71.

The lost motion connection between rod 73 and pivoted cover applying section is desirable as it enables the delivery mechanism to apply covers to cans of different sizes. Where covers are to be applied to cans of uniform size, the rod 67 may be formed with extending pins 67a which engage angle stop members 68a to limit the downward movement of the free end of the cover applying guide section.

The delivery mechanism, in operation, is adapted to receive a can and its cover at substantially the same time, at which time the side member 29 of the trough is arranged to co-operate with its companion side member 26 to arrest the can as it falls to a substantially horizontal position. The cover apply-

ing guide section at this time is supported at the upper limit of its range of movement by the rod 73. It will be noted, at this point, that the rod 73 is connected as heretofore described to the lower end of the lever 42 and that the link 34 by which the pivoted side member 29 is actuated by the guide block 36 is connected to the upper end of the lever 42. Thus during the interval that the can is supported in a substantially horizontal position, the cover applying guide section remains stationary and the cover therein may or may not roll toward the discharge opening 70, this, of course, depending upon the angle of inclination of the said section when the cover enters it. However, as the lever 42 is actuated to pivot the free end of the side member 29 of the reversing trough away from the fixed side member, the outer end of the cover applying guide section is lowered and the cover passes the can as it rolls by gravity down the bar 62 to come to rest in an upright position upon the supports 68. In the meantime, the can has been up-ended and as it moves toward the position at which it is to receive its cover, the cover is being lowered toward the plane in which the mouth of the can is moving. The parts of the mechanism are so co-ordinated that as the can reaches the cover receiving position its cover is lowered into its mouth, the cover supports 68 coming to rest upon the lip of the can in the manner described while the rod 73 continues to move downwardly a short distance. Thus, as the can continues to advance, the end of the cover applying guide section continues to lower and the cover is moved through the opening 70 against the action of the swinging gate. After the can cover has been applied, the cover applying guide section moves upwardly, it being understood that the pivoted side member 29 of the reversing trough has in the meantime been moved to condition the trough for receiving the next succeeding can, whereupon the cycle of operations described is repeated.

I claim as my invention:

1. In a can washing machine in which the cans are advanced while in an inverted position, the combination of mechanism for up-ending the cans comprising means for tipping a can forward, means supported against movement in the direction in which the can is tipped for receiving the can and means for operating said means last mentioned whereby the can is righted by gravity from the position in which it is received to a full up-ended position.

2. In a can washing machine in which the cans are advanced while in an inverted position, the combination of mechanism for up-ending the cans comprising means for tipping a can forward to overbalance it, means supported against movement in the direction in which the can is tipped for receiving the can in a substantially horizontal position and

means for operating said means last mentioned whereby the can is righted by gravity from the position in which it is received to a full up-ended position.

3. In a can washing machine in which the cans are advanced while in an inverted position, the combination of mechanism for up-ending the cans comprising means for tipping a can forward, means supported against movement in the direction in which the can is tipped for receiving the can and means for operating said receiving means to permit the continued downward movement of the bottom of the can during which movement the can is righted to a full up-ended position.

4. In a can washing machine in which the cans are advanced while in an inverted position, the combination of mechanism for up-ending the cans comprising means for tipping a can forward, means supported against movement in the direction in which the can is tipped for receiving the can in a substantially horizontal position and means for operating said receiving means to permit the continued downward movement of the bottom of the can during which movement the can is righted to a full up-ended position.

5. In a can washing machine in which the cans are advanced while in an inverted position, the combination of mechanism for up-ending the cans comprising means for tipping a can forward, means for receiving the can, means for operating said means last mentioned to release the forward end of said can while supporting it beyond the center of gravity in the direction of its rear end to permit the continued downward movement of the bottom of said can, during which movement the can is righted to a full up-ended position.

6. In a can washing machine in which the cans are advanced while in an inverted position, the combination of mechanism for up-ending the cans comprising means for tipping a can forward, means for receiving the can in a substantially horizontal position, means for operating said means last mentioned to release the forward end of said can while supporting it beyond the center of gravity in the direction of its rear end to permit the continued downward movement of the bottom of said can, during which movement the can is righted to a full up-ended position.

7. In a can washing machine in which the cans are advanced while in an inverted position, the combination of mechanism for up-ending the cans comprising means for tipping a can forward, means for receiving said can and means for separating said means last mentioned to permit the passage of the can therethrough during which movement the can is righted to a full up-ended position.

8. In a can washing machine in which the cans are advanced while in an inverted posi-

tion, the combination of mechanism for up-ending the cans comprising means for tipping a can forward so that it is overbalanced, means for receiving said can in a substantially horizontal position and means for separating said receiving means to permit the passage of the can therethrough during which movement the can is righted to a full up-ended position.

10. 9. In a can washing machine in which the cans are advanced in an inverted position, the combination of mechanism for up-ending the cans comprising means for tipping a can forward, means for receiving the can including a movable member and means for moving said member to release the forward end of the can while it is supported beyond the center of gravity in the direction of its rear end to permit the continued downward movement by gravity of the bottom of the can whereby it is righted to a full up-ended position.

10. 9. In a can washing machine in which the cans are advanced in an inverted position, the combination of mechanism for up-ending the cans comprising means for tipping a can forward, means for receiving the can including a fixed and a pivoted member and means for moving said pivoted member to release the forward end of the can while it is supported beyond its center of gravity in the direction of its rear end to permit the continued downward movement by gravity of the bottom of the can whereby it is righted to a full up-ended position.

11. In a can washing machine in which the cans are advanced in an inverted position, the combination of mechanism for up-ending the cans comprising means for tipping a can forward, means for receiving the can in a substantially horizontal position, said means including a fixed and a pivoted member which converge toward their bottoms and means for moving said pivoted member so that the can is supported only beyond its center of gravity in the direction of its rear end to permit the continued downward movement by gravity of the bottom of the can whereby the can is righted to a full up-ended position.

12. In a delivery mechanism of the class described, the combination of a cover applying member having its outer end formed to support a cover above the position in which it is to be applied to a can, said member being formed to provide a passageway through which the cover is guided as it moves to the outer end thereof and means for lowering the outer end of said member to lower the cover carried thereby into the mouth of a can as the latter passes therebeneath.

13. In a delivery mechanism of the class described, the combination of a cover applying member pivoted at its inner end and

formed at its outer end to support a cover above the position in which it is to be applied to a can, said member being formed to provide a passageway through which the cover moves as it is guided toward the outer end thereof and means for lowering the outer end of said member to lower the cover carried thereby into the mouth of a can as the latter passes therebeneath.

14. In a delivery mechanism of the class described, the combination of a cover applying member having its outer end formed to support a cover above the position in which it is to be applied and having an opening through which said cover moves as it is moved out of the end of said member, said member being formed to provide a passageway through which the cover is guided from the position in which it is received to the outer end thereof, a gate for normally closing the opening through which said cover passes and means for lowering the outer end of said member to lower the cover carried thereby into the mouth of a can as the latter passes therebeneath, said can being adapted to move said cover through said opening against the action of said gate.

15. In a delivery mechanism of the class described, the combination of a cover applying member adapted to receive a cover as it is moved forward vertically sidewise, said member being formed at its outer end to support a cover above the position in which it is applied and being formed between the outer end and the receiving end to provide a passageway through which the cover is guided as it moves to the said outer end and in which it is tipped over so that as it approaches the said outer end it is in the position in which it is to be applied and means for lowering the outer end of said member to lower the cover carried thereby into the mouth of a can as the latter passes therebeneath.

16. In a delivery mechanism of the class described, the combination of a cover applying member pivoted at its inner end and formed at its outer end to support a cover above the position in which it is to be applied and being formed between the outer end and the receiving end to provide a passageway through which the cover is guided as it moves to said outer end and in which it is tipped over so that as it approaches the said outer end it is in the position in which it is to be applied, means for lowering the outer end of said member to lower the cover carried thereby into the mouth of a can as the latter passes therebeneath and means for raising the outer end of said member to its original position.

17. In a delivery mechanism of the class described, the combination of a cover applying member formed at its outer end to support a cover in the position in which it is to be applied, means for supporting the said outer end above the cover applying position, the

said member being formed to provide a passageway in which the cover moves by gravity and means for lowering the outer end of said member to lower the cover carried thereby into the mouth of a can as the latter passes therebeneath.

18. In a delivery mechanism of the class described, the combination of a cover applying member formed at its outer end to support a cover in the position in which it is to be applied, means for supporting the outer end of said member above the cover applying position, the said member being formed with an opening through which the cover passes as it is moved out of the end of said member and with a passageway in which the cover moves by gravity to said opening, a gate for normally closing the said opening and means for lowering the end of said member to lower the cover carried thereby into the mouth of a can as the latter moves to a position therebeneath.

19. In a delivery mechanism of the class described, the combination of a cover applying member formed at its outer end to support a cover in the position in which it is to be applied, means for supporting the outer end of said member above the cover applying position, the said member being formed to provide a passage through which the cover rolls by gravity on its side and in which the cover is tipped over before reaching the outer end thereof and means for lowering the outer end of said member to lower the cover carried thereby into the mouth of a can as the latter passes therebeneath.

20. In a delivery mechanism of the class described, the combination of a cover applying member formed at its outer end to support a cover in the position in which it is to be applied, means for supporting the outer end of said member above the cover applying position, the said member being formed with an opening through which the cover passes out of the end thereof and with a passageway leading to said opening in which the cover moves by gravity into the position it occupies when applied, a gate for arresting said cover when it reaches the outer end of said member and means for lowering the outer end of said member to lower the cover carried thereby into the mouth of a can as the latter passes therebeneath, the can being adapted to carry said cover through said opening against the action of said gate.

21. In a can washing machine in which the cans are advanced while in an inverted position, the combination with mechanism for up-ending the cans and means for moving said up-ended cans to a cover receiving position, of a cover applying member adapted to support a cover above the mouth of a can and means for lowering said member to lower the cover carried thereby into the mouth of said can as the latter passes therebeneath.

22. In a can washing machine in which the

cans are advanced while in an inverted position, the combination with mechanism for up-ending the cans and means for moving said cans to a cover receiving position, of a cover applying member adapted to support a cover above the mouth of a can and means for lowering said member to lower the cover carried thereby into the mouth of said can as the latter passes therebeneath, said can removing said cover from said cover applying member as it passes from beneath the same.

23. In a can washing machine in which the cans are advanced while in an inverted position, the combination with mechanism for up-ending the cans, comprising means for tipping a can forward, means for receiving the can, means for operating said receiving means whereby the can moves to a full up-ended position by gravity and means for moving said up-ended can to a cover receiving position, of a cover applying member adapted to support a cover above the mouth of the can and means for lowering said member to lower the cover carried thereby into the mouth of said can as the latter passes therebeneath.

24. In a can washing machine in which the cans are advanced while in an inverted position, the combination with mechanism for up-ending the cans, comprising means for tipping a can forward, means for receiving the can, means for operating said receiving means whereby the can moves toward an upright position by gravity, a support for receiving said can in an up-ended position and means for moving said can along said support to a cover receiving position, of a cover applying member adapted to support a cover above the mouth of said can and means for lowering said member to lower the cover carried thereby into the mouth of said can as the latter passes therebeneath.

25. In a can washing machine in which the cans are advanced while in an inverted position, the combination with mechanism for up-ending the cans and means for moving said cans as up-ended to a cover receiving position, of a cover applying means comprising a movable guide adapted to receive a cover from said machine as it is rolled along its side and formed to right said cover and support it above the mouth of a can and means for lowering said guide to lower said cover into the mouth of said can as the latter passes therebeneath.

26. In a can washing machine in which the cans are advanced while in an inverted position, the combination with mechanism for up-ending the cans and means for moving said cans as up-ended to a cover receiving position, of cover applying means comprising a movable guide adapted to receive a cover from said machine as it is rolled along its side and in which the cover rolls by gravity to a point above the position at which it is to

be applied, and means for lowering said guide to lower said cover into the mouth of said can as the latter passes therebeneath.

27. In a can washing machine in which the cans are advanced while in an inverted position, the combination with mechanism for up-ending the cans comprising means for tipping a can forward, means for receiving said can, means for operating said receiving means whereby said can is righted to a full up-ended position by gravity and means for moving said up-ended can to a cover receiving position, of a cover applying member adapted to receive a cover and support it above the mouth of a can and means for lowering said member to lower said cover into the mouth of said can as the latter passes therebeneath, said means being effective to condition the mechanism for up-ending the can which is to receive the next succeeding cover.

28. In a can washing machine in which the cans are advanced while in an inverted position, the combination with mechanism for up-ending the cans comprising means for tipping a can forward, means for receiving said can, means for operating said receiving means whereby said can moves by gravity toward a full up-ended position, a support upon which said can is received in such position and means for moving said can along said support to a cover receiving position, of a movable cover applying member through which the cover moves by gravity adapted to receive a cover and support it above the mouth of a can, and means for lowering said member to lower said cover into the mouth of said can as the latter passes therebeneath.

29. In a can washing machine in which the cans are advanced while in an inverted position, the combination with mechanism for up-ending the cans comprising means for tipping a can forward, means for receiving said can, means for operating said receiving means whereby said can moves to a full up-ended position by gravity, a support upon which said can is received in such position and means for moving said can along said support to a cover receiving position, of a cover applying member adapted to support a cover for said can in advance thereof and above its mouth and means for lowering said member to lower said cover into the mouth of said can as the latter passes therebeneath, said can carrying said cover with it out of said member as it continues past the cover receiving position.

30. In a can washing machine in which the cans are advanced while in an inverted position, the combination with mechanism for up-ending the cans comprising means for tipping a can forward, means for receiving said can in a substantially horizontal position, means for operating said receiving means so that said can is supported only be-

yond the center of gravity in the direction of its rear end thereby permitting the bottom of said can to continue its downward movement, a support upon which said can comes to rest and means for moving said can along said support toward a cover receiving position, of a cover applying member adapted to support a cover for said can in advance thereof and above its mouth and means for lowering said member to lower said cover into the mouth of said can as the latter passes therebeneath.

31. In a can washing machine in which the cans are advanced while in an inverted position, the combination with mechanism for up-ending the cans comprising means for tipping a can forward, means for receiving the can, said means including a movable member, means for moving said movable member so as to support the can only beyond the center of gravity in the direction of its rear end to permit continued downward movement of the bottom end of the can, a support upon which said can drops upon its bottom and means for moving said can along said support to a cover receiving position, of a cover applying member adapted to support a cover for said can in advance thereof and above its mouth and means for lowering said member to lower said cover into the mouth of said can as the latter passes therebeneath.

32. In a can washing machine in which the cans are advanced while in an inverted position, the combination with mechanism for up-ending the cans comprising means for tipping a can forward, means for receiving said can as it falls, said means including a pivoted member, means for moving the pivoted member so as to support the can only beyond its center of gravity in the direction of its rear end to permit continued downward movement of the bottom end of the can, a support upon which said can drops upon its bottom and means for moving said can along said support to a cover receiving position, of a cover applying member adapted to support a cover for said can in advance thereof but above its mouth and means for lowering said member to lower said cover into the mouth of the can as the latter passes therebeneath.

33. In a can washing machine in which the cans are advanced while in an inverted position, the combination with mechanism for up-ending the cans comprising means for tipping a can forward, means for receiving the can as it falls, said means including a fixed member and a movable member, said members converging in the direction of their bottoms and adapted to support said can in a substantially horizontal position, means for moving said movable member so that the said can is supported only beyond the center of gravity in the direction of its rear end to permit the continued downward movement

of the bottom of the can, a support upon which said can drops upon its bottom and means for moving said can along said support, of a cover applying member adapted to support a cover for said can in advance thereof but above its mouth and means for lowering said member to lower said cover into the mouth of said can as the latter passes therebeneath.

10 In testimony whereof I affix my signature.
FRANK F. WOLF.
